UNITED STATES PATENT OFFICE.

EMANUEL WAGNER, OF TOKOD, HUNGARY.

STOVE AND FURNACE.

Application filed April 1, 1926, Serial No. 99,006, and in Austria December 15, 1924.

The present invention relates to improvements in stoves and furnaces, and more particularly to that type which contains a magazine for the fuel. The invention is especially adapted for use in connection with bituminous or like coal.

Coals of the type mentioned contain a considerable amount of volatile combustible matter, forming a large proportion of the heat producing or heat developing power of the fuel. When fuel of this type is heated, it soon loses its combustible gases and thus a great part of its heating value. It is a well-known fact that fuels of this type develop at the start a considerable amount of heat, but, after the volatile matter has been consumed, the heat generated by the residue decreases greatly. Therefore, in order to burn such fuel continuously and with a uniform rate of heat emission, it must be kept cool until it reaches the combustion chamber. This has been accomplished heretofore by providing a fuel container or magazine which is kept isolated from the heat emitting or heat radiating surface of the stove by an insulating layer of air, the combustion chamber being placed more or less underneath the fuel magazine and adjoining the heat emitting or heat radiating surface. In practice it has been found, however, that stoves constructed in accordance with these principles are too complicated for domestic use, they containing so many doors and openings that their proper handling requires special knowledge, which cannot be expected from persons usually attending the same. Even if properly handled, such stoves and furnaces possess objectionable features, which make them unsuitable for general use. For instance, gases accumulate gradually in the fuel magazine, which cause frequent explosions, or the gases escape through the doors of the stove or furnace and pollute the air of the rooms to be heated or in which they are located. The reason for this is that an upward current of air is generated in the fuel magazine by the heat in the combustion chamber located underneath the magazine. If the doors of the magazine do not make an air-tight clo-

sure, or are opened in order to replenish the fuel, the gases are ignited, explode and enter the room.

The main object of the present invention is to provide a stove or furnace wherein the difficulties above referred to are overcome.

Generally speaking, the invention consists in causing a downward draught of air in the fuel magazine, whereby the coal gases are caused to pass through the incandescent fuel bed in the combustion chamber and are thus completely consumed, and in so arranging the elements of the stove or furnace that the direction of flow of said gases remains undisturbed even if the door of the fuel magazine is opened.

One of the many possible embodiments of the invention is illustrated in the accompanying drawings, in which:—

Figure 1 is a central vertical section taken through a stove or furnace constructed in accordance with the present invention; Fig. 2 is a section taken on line 2—2 of Fig. 1; and Fig. 3 is a section taken on line 3—3 of Fig. 2.

In the drawings, the numeral 10 indicates the combustion chamber of a stove or furnace, it including a horizontally extending grate 11, from which rises an inclined grate 12, the same slanting toward the front of the combustion chamber. The last-mentioned grate may be removed from the combustion chamber through an opening 13, closed by a door 14. In alignment with the inclined grate rises from the combustion chamber a fuel magazine 15, the inclined grate forming, as it were, the bottom of the said magazine, the fuel sliding down the said bottom on to the horizontal grate 11. As appears from Fig. 1 of the drawings, the fuel magazine is disposed somewhat forward of that portion of the combustion chamber in which the actual combustion of the fuel takes place. The products of combustion, passing over a bridge 16 into a heating body 17 hereinafter to be described, have thus no tendency to flow into the fuel magazine and to heat the fuel contained therein. The heating body 17 may be of any suitable construction and design and may serve any purpose, for in-

stance it may heat air, water or generate steam, as required. In the case illustrated, it comprises a closed body, having an outlet 18 near its top, the said outlet being connected with the chimney. Through the heating body extends a plurality of tubes 19, open both at their bottom and top, whereby the air circulating therethrough is heated. As appears from Fig. 1 of the drawings, the magazine and heating body are separated by an insulating layer of air, whereby the fuel in the magazine is prevented from becoming overheated by the heat emanating from the heating body.

15 Below the horizontal grate 11 is provided the usual ash pit 20, containing, if necessary, an ash receiver or ash pan 21. The ash pit is also provided with a door, denoted by the numeral 22, which may be made integral with the combustion chamber door 14. On the ash pit door may be provided a shutter 23, for regulating the air supply passing into the ash pit and thence into the combustion chamber.

25 The top of the fuel magazine 15 is closed by a door 24, provided with a shutter 25 of any suitable construction, to regulate the flow of air into the said magazine. The upper portion of the fuel magazine is connected with the ash pit by air pipes or air conduits 26 and 27, and the ash pit is connected with the combustion chamber by air passages 28. The outlets of the passages 28 in the combustion chamber are disposed adjacent the firebridge and above the fuel bed. Immediately below the top of the fuel magazine is located within the latter a damper 29, for a purpose hereinafter to be described.

40 The operation of the stove or furnace is as follows: Assuming that the shutter 23 on the ash pit is in its closed position, it is obvious that air, entering through the shutter controlled opening in the magazine door 24, flows, in part, through the air pipes 26 and 27 into the ash pit, passing thence through the grates 11 and 12 into the combustion chamber. Part of the air flowing through the pipes 26 and 27 flows through 50 the passages 28 directly into the combustion chamber immediately above the coal bed therein, thereby insuring a perfect combustion of the gases generated. Part of the air entering the top of the fuel magazine flows downwards through the said magazine, thereby scavenging the same, that is to say removing the gases accumulated or generated in the coal supply and leading such gases into the combustion chamber. Owing 55 to this arrangement, obviously, gases cannot leave the stove or furnace even if the magazine door 24 is wide open. In order to restrict the fire to the fuel in the combustion chamber and to prevent its spreading to the coal in the magazine, the damper

29 must be set in order to reduce the air moving downwards through the fuel magazine to the proper amount.

The products of combustion pass through the heating body 17, giving up their heat or part of their heat to the air flowing through the tubes 19 extending through the said heating body, and pass then through the outlet to the chimney.

If the shutter 25 on the fuel magazine 75 door 24 is kept in its closed position and the shutter 23 on the ash pit door 22 is set to open position, air will move in the air pipes 26 upwards, but the operation of the stove remains the same as above described, 80 a downward draught of air in the fuel magazine being induced.

Instead of the heating body 17 hereinabove described, any other heating body 85 may be used, for instance an ordinary stove may be connected to the combustion chamber and the elements co-operating therewith.

It is to be noted that the handling of the stove or furnace herein described does not require special knowledge, as only a single 90 air regulating device must be set by the attendant, that is to say either the shutter on the magazine fuel door or the shutter on the ash pit door. The fuel in the magazine cannot catch fire if the damper 29 is once 95 set to allow the passage of only as much air through the fuel as is necessary for removing the combustible gases therefrom and for carrying these gases down into the combustion chamber.

It is obvious that, while herein the air inlets have been described as being formed either on the door of the fuel magazine or on the ash pit door, they may be provided in any other place without departing from the invention, which lies mainly in the provision of means for inducing a downward draught of air through the fuel supply in the magazine, so as to scavenge and cool the same for the purposes above set forth.

105 What I claim is:

1. A stove or furnace comprising a combustion chamber, a fuel magazine associated therewith having air inlets adjacent its top, and air tubes leading from the top portion of said magazine to points below the grate in said combustion chamber, part of the air entering through said air inlets flowing through said air tubes and part thereof through said fuel magazine.

115 2. A stove or furnace according to claim 1, comprising means for regulating the amount of air flowing through said magazine.

3. A stove or furnace according to claim 1, comprising means disposed in the upper portion of said magazine for regulating the amount of air flowing through said magazine.

120 4. A stove or furnace according to claim 130

- 1, comprising passages connecting the space 1, said fuel magazine being offset in relation to the grate in said combustion chamber. 10
below the grate with said combustion chamber, said passages terminating in the combustion chamber above the fuel therein.
- 5 5. A stove or furnace according to claim 1, comprising a heat emitting body connected with said combustion chamber.
- 1, comprising passages connecting the space 1, said fuel magazine being offset in relation to the grate in said combustion chamber. 10
below the grate with said combustion chamber, said passages terminating in the combustion chamber above the fuel therein.
6. In a stove or furnace according to claim 1, comprising a heat emitting body connected with said combustion chamber.

Signed at Tokod, in the county of Esztergom, in the Kingdom of Hungary, this 1st day of March, 1927.

EMANUEL WAGNER.
